(57) **CLAIM**

The ornamental design for a display panel or screen with a graphical user interface, as shown and described.

DESCRIPTION

FIG. 1 is a front elevational view of display panel or screen with a graphical user interface showing our new design; and, FIG. 2 is a reduced front elevational view thereof.

The even broken lines showing of a display panel or screen and other elements form no part of the claimed design. The dot-dash broken lines define boundaries of, but not included in, the claimed design.
